(57) **CLAIM**

The ornamental design for a chair, substantially as shown and described.

DESCRIPTION

FIG. 1 is a perspective view of the chair;

FIG. 2 is a plan view of the top of the chair;

FIG. 3 is an elevation view of the front of the chair;

FIG. 4 is an elevation view of the one side of the chair;

FIG. 5 is an elevation view of the other side of the chair;

FIG. 6 is an elevation view of the rear of the chair; and,

FIG. 7 is a plan view of the bottom of the chair.

The broken lines shown in the drawings are for illustrative purposes only and form no part of the claimed design.
